UNITED STATES PATENT OFFICE.

JOHN ELLWOOD LEE, OF CONSHOHOCKEN, PENNSYLVANIA.

SPOOL-CARRIER FOR BRAIDING-MACHINES.

SPECIFICATION forming part of Letters Patent No. 478,341, dated July 5, 1892.

Application filed February 27, 1891. Serial No. 383,113. (No model.)

To all whom it may concern:

Be it known that I, JOHN ELLWOOD LEE, a citizen of the United States, and a resident of Conshohocken, Pennsylvania, have invented 55
5 an Improved Spool-Carrier for Braiding-Machines, of which the following is a specification.

The object of my invention is to so construct the traveling spool-carriers or thread-carriers 10 of braiding-machines as to simplify and facilitate the manipulation and operation of the braiding-machine, particularly in narrowing or widening operations, and also for the formation of selvage openings, where desired, in 15 the tubes being braided. This object I attain by making the carrier in two parts readily detachable from each other, so that the thread-carrying part may be quickly removed from or replaced upon the traveling 20 part without removing the latter from the guiding-grooves of the race plate or plates.

In the accompanying drawings, Figure 1 is a side view of a carrier of ordinary construction. Fig. 2 is a side view of one form of my 25 improved carrier. Fig. 3 is an end elevation of the same, but with the spool, catch, and tension-weight removed. Fig. 4 is a view of my improved spool or thread carrier corresponding with Fig. 2, but showing the thread 30 or spool carrier part detached from the traveler end of the device. Fig. 5 is an inverted plan view of the upper part of my two-part carrier, drawn to a larger scale; and Fig. 6 is a perspective view, to the same scale, of the 35 traveler part, from which the upper part has been detached.

Referring to Fig. 1, which shows an ordinary form of thread or spool carrier for a braiding-machine, B is the spool, mounted to 40 turn upon the spindle S, carried by the traveler part T, which is adapted to run in the grooves of the race-plate. A post P carries the movable tension-weight E for the thread and also the stop-catch F for the notched top 45 of the bobbin.

I may here state that while I have shown my improvements as applied to this style of carrier, as hereinafter described, I do not wish to restrict myself to any special style of construction, as the details may be varied without departing from my invention.

In operating a machine having the ordinary carriers with which I am acquainted it is customary to provide for the narrowing operation by periodically stopping the machine, 55 breaking one or more ends, and wrapping each loose end around the top of its carrier, and then restarting the machine to go on braiding with a reduced number of threads. Similarly, in widening, the machine has to 60 be stopped and threads from additional spools connected up. These operations are somewhat tedious, and in order to make them less so, and also for a further purpose explained hereinafter, I construct the thread or spool 65 carrier in two parts readily detachable from and attachable to each other. One part is that which carries the spool or thread, (and stop-catch and tension-weight where these parts are used, as above described,) while the other 70 part is the lower traveler end of the carrier, which travels in the grooved race-plate of the machine.

Any convenient form of attaching means may be provided between the two parts, and 75 I do not wish to restrict myself to any particular means; but I have found in practice that the connecting devices illustrated in Figs. 2, 3, 4, 5, and 6 are suitable for the purpose. In the construction illustrated the lower traveler part T² is provided on its upper side with an undercut groove t and a notch t' on one side thereof. The under side of the upper detachable part T' is provided with an undercut tongue p, adapted to fit into the undercut groove t of the traveler part T², and a spring-catch p', carried by this tongue, is adapted to engage with the notch t' when the two parts are fitted, so as to lock them together, as illustrated in Figs. 2 and 3. By 80 pressing on the projecting end of this spring-catch, however, the thread or spool carrying part can be readily detached from the traveler part T². Thus in the narrowing operation when it is desired to reduce the number 85 of threads the machine is stopped and the corresponding thread or spool carrying parts detached from their respective traveler parts and lifted out and above the braid. In practice it has been found that this is a much 90 quicker way of manipulating than by the old method above described. Furthermore, I can 95 100

with my improved two-part carrier accomplish an important object which was not possible with the old form of irremovable thread or spool carrier—namely, where it is desired 5 to form a selvage opening in a braided tube the machine provided with my carriers is repeatedly stopped as the carriers successively come to a certain point where they would ordinarily pass each other. The spool or thread 10 carrying part of each of the meeting carriers is removed from its lower traveling part and is transferred to the traveling part of the other carrier going in the opposite direction, so that at this point each successive thread in 15 the braiding will be turned back, as it were, to be carried back in the opposite direction from that in which it was traveling, and a sel-

vage-opening of any desired length may be thus formed in the braided tube.

I claim as my invention—

20 A thread or spool carrier for braiding-machines, consisting of a traveler part adapted to run in the grooved race-plate of the machine and an upper part consisting of a spindle for the thread-spool and a guide-post, such 25 upper part being readily detachable from the said lower part, substantially as described.

In testimony whereof I have signed my name to this specification in the presence of two subscribing witnesses.

J. ELLWOOD LEE.
